UNITED STATES PATENT OFFICE.

PETER C. DUBE, OF ESCANABA, MICHIGAN.

MECHANICAL MASSAGING DEVICE.

1,364,623.

Specification of Letters Patent.

Patented Jan. 4, 1921.

Application filed January 19, 1920. Serial No. 352,258.

To all whom it may concern:

Be it known that I, PETER C. DUBE, a citizen of the United States, and a resident of Escanaba, in the county of Delta and State of Michigan, have invented a new and useful Improvement in Mechanical Massaging Devices, of which the following is a full, clear, and exact description.

My invention relates to improvements in mechanical massaging devices, and it consists in the combinations, constructions, and arrangements herein described and claimed.

An object of my invention is to provide a device for massaging by mechanical means a number of the muscles of the body at the same time.

A further object of my invention is to provide a device of the type described that will massage the muscles of the body in a more uniformly effective manner than is possible when the massaging is done manually.

A further object of my invention is to provide muscle massaging means in a device of the type described that may be adjusted to massage muscles of varying sizes.

Other objects and advantages will appear in the following specification, and the novel features of the invention will be particularly pointed out in the appended claims.

My invention is illustrated in the accompanying drawings, forming part of this application, in which—

Figure 1 is a side view of the device,

Fig. 2 is an end view of the same,

Fig. 3 is a top plan view of the device shown diagrammatically,

Fig. 4 is a detailed view of a portion of the device,

Fig. 5 is a detailed view of a portion of the device.

In carrying out my invention I provide a supporting frame having end portions 1 and 2 connected and held rigidly in position by rods 3. A plurality of suspension hangers 4 have their upper ends slidably secured to a supporting bar 5 which has its ends secured in the end portions 1 and 2 near the middle of their upper edges. Supports 6 adapted to receive the body of a man are carried by and secured to the lower ends of the suspension hangers 4.

A stub shaft 7 is rigidly secured in the end portion 2 near the center of the latter. A drive pulley 8 is rotatably mounted thereon. A number of driven shafts 9—four be-

ing shown in the accompanying drawings—are positioned in parallel alinement and are journaled to rotate upon ball bearings (not shown) in the end portions 1 and 2 near the upper edges of the latter. Gears 10 are keyed to ends of the driven shafts 9 which extend through the end portion 2. The gears 10 are actuated by the gears 11, which are mounted to rotate upon stub shafts 12, either directly or through the medium of intermediate gears 13, which are mounted to rotate upon stub shafts 14, so that all gears 10 are rotated simultaneously, alternate gears 10 turning in the same direction. The stub shafts 11 and 14 are secured to the end portion 2 in the positions indicated in Fig. 2 of the accompanying drawings.

The gears 11 mesh with and are driven by the gear 15 which is mounted to rotate upon a stub shaft 16. The latter is secured to the end portion 2. A crank arm 17 has one end pivotally connected eccentrically to the gear 15 and has its other end pivotally fastened to the drive pulley 8. A revolution of the drive pulley 8 will impart an oscillatory movement to the gear 15. The oscillatory movement of the gear 15 may be lengthened or shortened by adjusting the connection of the crank arm 17 toward or away from the centers of the drive pulley 8 and the gear 15.

A plurality of sprocket wheels 18 are feathered to the driven shafts 9 between the end portions 1 and 2 and may be slidably moved therewith. Chains 19 engage the teeth of the sprocket wheels 18. Straps 20 are joined to the ends of the chains 19. Adjustable muscle engaging straps 21 are secured to the lower portion of the straps 20 substantially as shown in Fig. 4 of the accompanying drawings. The straps 20 may be adjusted in length to insure rigidity when the muscle engaging straps 21 are adjusted to engage different muscles of a man's body 22 shown resting upon the supports 6 in Fig. 1 of the accompanying drawings.

From the foregoing description of the various parts of the device, the operation thereof may be readily understood. The drive pulley 8 is rotated by any suitable power means. In the embodiment of my invention illustrated in the accompanying drawings, the power actuating the drive pulley is transmitted through the belt 23 from a motor 24. The drive pulley 8 imparts an oscillatory movement to the sprocket wheels 18 by means of the crank arm 17, the gear 15,

the gears 11, the gears 13, the gears 10, and the driven shafts 9 which are arranged as described. Alternately positioned shafts will be moved in the same direction.

5 The oscillatory movement of the sprocket wheels 18 imparts a vertical reciprocating movement to the chains 19 and the straps 20. Consequently, when the different muscles of the body are engaged by the muscle 10 engaging straps 21 which are fastened to the straps 20, the vertical reciprocating movement of the latter massages the muscles thoroughly and uniformly.

The reciprocating movement of the straps 15 20 may be lengthened or shortened by adjusting the connections of the crank arm 17 with the drive pulley 8 and the gear 15 in the manner described. Consequently, the muscles will be massaged more forcibly as 20 the reciprocating movement of the strap 20 is lengthened. It will therefore be obvious that my device is suitable for use in massaging muscles of both mature and immature persons in varying physical conditions.

25 It is suitable for the athlete who has well developed muscles and also for the invalid. It is believed that my device will be of incalculable benefit to persons suffering from diseases benefited by treatment of the muscles since it affords a means for readily massaging the muscles uniformly in a manner neither too gentle nor forcible for beneficial results.

I claim:

35 1. In a device of the type described a supporting frame comprising parallel end portions, a plurality of rods connecting said end

portions, body supporting means adjustable vertically and slidably longitudinally on said supporting frame, a plurality of straps suspended from said supporting frame, each of said straps being formed into a loop, a second strap secured to the lower portion of each of said first named straps, said second named straps being adapted for fastening 45 around portions of the body to engage the muscles thereof, and means for simultaneously reciprocating the side portions of the loops formed by said first named straps, whereby the muscle engaging straps effectually massage the muscles engaged thereby. 50

2. A device of the type described consisting of parallel end portions connected by a plurality of rods, a supporting rod having its ends secured to the end portions, suspension straps having their upper ends slidably secured to said supporting rod, body rests fastened to the lower ends of said suspension straps shafts disposed between and having their end rotatably mounted in said 60 end portions, a plurality of sprockets keyed to said shafts, a chain arranged to engage each of said sprockets intermediate its length, a strap having its ends secured to the ends of each of said chains, a muscle engaging strap secured to said second named strap at substantially the middle point thereof, said last named muscle engaging strap being adapted to be fastened around portions of the body, and mechanical means for 65 operating said shafts, whereby the muscles engaged by the muscle engaging straps are effectually massaged. 70

PETER C. DUBE.
